(57) **CLAIM**

The ornamental design for a display screen with graphical user interface, as shown and described.

DESCRIPTION

FIG. 1 is a first image for a display screen with graphical user interface showing my new design; and, FIG. 2 is a second image for a display screen with graphical user interface showing my new design.

The broken lines showing of the display screen with graphical user interface are for environmental purposes only and form no part of the claimed design. The appearance of the animated user interface sequentially transitions between FIGS. 1 to 2. The process or period in which one image transitions to another image forms no part of the claimed design.
